JOHN HARRIS, OF SHEFFIELD, ENGLAND

MECHANICAL ORE-ROASTING FURNACE

Application filed May 21, 1928, Serial No. 279,509, and in Great Britain June 2, 1927.

This invention relates to mechanical ore roasting furnaces of the type comprising a series of super-imposed hearths through which a rabble shaft extends with arms operating over the various hearths on which the ore is successively rabbled in its passage through the furnace, the object of the invention being to reduce or to avoid the formation of dust in the furnace by providing improvements in the method and means of passing the ore from hearth to hearth. A further object of the invention is to provide improved flues for the draught and for the passage of gas through the furnace for a like purpose.

Assuming an even draught through the furnace the chief cause of dust being formed in a furnace of the type referred to appears to be due to the fall of the ore from hearth to hearth, the finer particles rising in dust as each batch of ore falls and being carried with the gases through the furnace to create damage in subsequent operations. To avoid dust from this cause it has been proposed to pass the ore from an upper hearth to a lower one through a conduit screening it from the draught through the furnace, the conduit moving with the rabble shaft and having an outlet opening at its lower trailing edge adjacent to the rabbling level of the lower hearth.

According to the present invention, however, the passage of ore from an upper hearth to a lower one is effected in stages of which one is into and through a fixed conduit depending from the upper hearth and another is into and through a moving conduit brought to register with the fixed one by the rabble shaft or arm. Preferably there is an intermediate stage of the ore passage, the ore being temporarily retained in the fixed conduit which is closed by a platform on the rabble shaft or arm, the moving conduit opening into the platform and being subsequently brought to register with the fixed conduit. Thus not only is the ore screened from the furnace draught by the conduits in its passage from hearth to hearth, but each time it falls it is from a smaller height than that between the hearths and hence the tendency to cause dust

is also reduced. The rabble arm of the lower hearth may pass below the fixed conduit after it has received the ore and before the moving conduit receives it, especially when the ore is delivered at the outer edge of the circular path traversed by the rabbling arm.

In a convenient construction a fixed ore conduit opens through an upper hearth in the path of one end of the rabble arm operating thereon and depends to a point above the rabble arm on the hearth below. A moving conduit is carried by the lower rabble arm or by the shaft and is disposed to extend the fixed conduit to the rabbling level of the lower hearth once in each revolution of the rabble shaft. Preferably the moving conduit opens at its upper end in a platform carried by the lower rabble arm or by the shaft, the platform extending in advance of the moving conduit to close the lower end of the fixed one. The moving conduit is preferably provided with an outlet opening at its lower trailing edge so that the ore is deposited therethrough as the conduit moves around the shaft.

In single shaft furnaces the ore is, of course, delivered alternately adjacent to the rabble shaft and adjacent to the path of the free end of the rabble arm on successive hearths, and the platforms, especially those of the hearths receiving ore adjacent to the rabble shaft, may be comprised by an annulus or by a sector of an annulus concentric with the shaft.

The platform of each hearth receiving the ore adjacent to the path of the outer end of the rabble arm is preferably carried at that end of the arm, extending in advance thereof to close the fixed conduit and in rear thereof to carry the moving conduit, the rabble arm of the upper hearth being substantially vertically above the arm of the lower hearth carrying the platform.

It is the usual practice in cylindrical furnaces for the ascending gases and draught through the furnace to pass through the openings in the various hearths down which the ore falls. Such meeting of ascending gas with falling ore is another pernicious cause of dust, and it is therefore important to avoid it by providing flues for the ascending gases

separate from the ore passages. There is no difficulty in doing this in rectangular furnaces, for it is usual to arrange the flues in the corners out of the path of the rabble arms and the ore moved thereby. In applying the invention to a cylindrical furnace, however, where the rabble arms traverse the whole of the hearth surface, it is necessary to provide special flues for the ascending gases, since although the ore conduits of the invention screen the falling ore from the ascending gases, it is not desirable to rely on the ore passages for use as gas flues because the draught through the furnace would be choked each time the ore passed from one hearth to another, resulting in another cause of dust and impairing the working of the furnace, whilst the number of combined ore passages and gas flues which would be necessary would result in inefficient working. In the case of cylindrical furnaces, therefore, the special flues referred to above are disposed at the circumference of each hearth, extending around the edge of the path of the rabble arm on each hearth with an inlet below the hearth and an outlet above the ore level thereon. These flues may be of known construction comprising a central portion built in the furnace wall between two hearths with an opening below each of them, but according to a feature of the invention the central portion of each flue has a lower enlargement replacing part of the lower hearth and providing its inlet and has also an upper enlargement replacing part of the upper hearth and providing the flue outlet. The flues may be reinforced by radial plates to take the thrust of the arches which provide the hearths.

The flue or flues around the rabbling path of one hearth are preferably substantially diametrically opposite those around the rabbling path of the hearth above or below it. In this manner the gases and draught through the furnace pass in a zigzag fashion across successive hearths whilst they are effectually screened from contact with the ore during the passage of the latter from hearth to hearth.

In the accompanying drawings:

Figure 1 is a sectional elevation of a cylindrical mechanical ore roasting furnace according to the present invention.

Figure 2 is a sectional plan on the line 2—2 of Figure 1.

Figure 3 is an enlarged sectional elevation of part of the furnace taken on the line 3—3 of Figure 2.

Figure 4 is an enlarged sectional elevation of the central portion of Figure 1 showing the parts in position just before the passage of ore from one hearth to another.

Figure 5 is a plan of Figure 4.

Figures 6 and 7 are views similar to Fig-

ures 4 and 5 showing the parts in a subsequent position.

Figure 8 is a sectional elevation on a larger scale on the line 8—8 of Figure 2.

Figure 9 is a sectional plan on the line 9—9 of Figure 8.

Like reference numerals indicate like parts throughout the drawings.

The drawings show the invention applied to a cylindrical mechanical ore roasting furnace which comprises a cylindrical wall 10 supporting a series of superimposed hearths of which four marked respectively 11, 12, 13 and 14 are shown in section in Figure 1. A rabble shaft 15 extends through the series of superimposed hearths, and is provided with arms 16 carrying rabbles 17 operating over each of the hearths. These hearths are of arched or dished formation, their edges resting against seating blocks 18 incorporated in the cylindrical wall 10 and supported by hoop-like girders. The space between the arched hearths 11 and the rabbles 17 is normally filled by stationary ore which provides the rabbling level 19 as indicated in Figure 1. Means, not illustrated, are provided for rotating the rabble shaft 15 and for delivering ore on to the uppermost hearth 11 which merely dries the ore, the roasting operation commencing after the ore has entered the interior of the furnace.

The ore is delivered, in the construction illustrated, on to the drying hearth 11 adjacent to the rabble shaft 15 and is gradually moved to the periphery of that hearth by the rabbles 17 operating above it. It then drops on to the hearth 12 on which it is moved towards the shaft 15 by the rabbling arm of that hearth, dropping on to the hearth 13 adjacent to the rabble shaft and being rabbed thereon towards the wall 10. This alternate travel of the ore from periphery to shaft and from shaft to periphery on successive hearths is continued throughout the furnace until the roasted ore is discharged at an outlet not shown on the drawing. Air for oxidation or combustion, with or without heating gases, is supplied to the various hearths through suitable ports, not shown, and leaves the furnace through the port 20 which is connected to the chimney by way of the Glover tower in the case of a furnace used to roast ore for the production of sulphuric acid.

The present invention provides improved means for screening the ore, during its passage from an upper to a lower hearth, from the draught through the furnace and for conducting it so screened, past the space traversed by the arm and its rabbles to the rabbling level of the lower hearth. At the ore passage from the hearth 12 to the hearth 13 adjacent to the rabble shaft 15 such means (illustrated to a larger scale in Figures 4, 5, 6 and 7) comprise a fixed ore conduit 21 opening through the upper hearth 12 below the

path of the end rabble 17 which is nearest to the shaft 15 and operates over the hearth 12. The conduit 21 depends to a point above the rabble arm 16 operating over the hearth 13 and a platform 22 is carried by this arm 16 or by the shaft 15 in such a position as to be capable of closing the conduit 21. In the construction shown in Figures 4, 5, 6 and 7 the platform 22 is in the form of a flanged 10 annulus concentric with the shaft 15 and with the lower end of the conduit 21 situated between its flanges.

A moving conduit 23 is carried by the platform 22 and opens at its upper end in the 15 platform. The moving conduit extends down to the rabbling level 19 of the hearth 13, the arrangement and disposition of the parts being such that the opening of the moving conduit 23 in the platform is brought to register with the fixed conduit 21 as the shaft 15 rotates.

In operation the ore rabbled by the arm 16 on the hearth 12 will be moved towards the shaft 15 and a batch of ore will be delivered 25 into the fixed conduit 21 at each revolution of the shaft. This batch of ore will be temporarily retained in the conduit 21 since its lower end is closed by the platform 22 or by the bedding ore thereon, Figures 4 and 5 illustrating the relative position of the parts just before a batch of ore is delivered into the 30 fixed conduit 21. As the shaft 15 rotates the moving conduit 23 is brought to register with the fixed conduit 21, whereupon the ore 35 temporarily retained in the latter by the platform 22 will fall into the moving conduit which is provided with an outlet 24 opening at its lower trailing edge as indicated in Figure 6 which illustrates the position of the 40 parts when the ore passes from the fixed conduit 21 into the moving one 23. During the further revolution of the shaft 15 the ore in the moving conduit 23 will be gradually deposited at the rabbling level of the hearth 13, 45 subsequently to come under operation of the rabbles 17 moving over that hearth.

It will be understood that the operative portion of the platform 22 retaining ore in the fixed conduit 21 is the portion which extends in advance of the conduit 23 up to the 50 fixed conduit at the moment when the ore is delivered into the latter. The remainder of the annulus forming the platform 22 may be dispensed with if desired, although it is preferred to retain it, first to seal the conduit 21 from the furnace draught and secondly to facilitate the fitting of the platform and moving conduit to the shaft 15.

Figures 8 and 9 illustrate the ore passage 55 from the hearth 13 to the hearth 14, at the outer end of the arm 16 adjacent to the wall 10. In this case the fixed conduit 21 extends above the arch of the hearth 13 to the rabbling level 19 thereon and the platform 22 is carried at the end of the arm 16 operating over

the hearth 14, the platform being suitably formed to engage the end of the arm. The arm 16 operating over the hearth 13 is preferably substantially vertically above the arm of the lower hearth, the platform 22 extending sufficiently in advance of the arm carrying it to close the fixed conduit 21 when the rabbles of the upper hearth deliver a batch of ore into the conduit. The platform 22 carries the moving conduit 23 on the rear side of the arm 16 so that ore deposited in the fixed conduit 21 is temporarily retained therein by the platform 22 until the arm of the hearth 14 has passed the conduit 21. The ore then passes into the moving conduit 23 and is thence deposited at the rabbling level 75 of the hearth 14.

The ore is delivered into the furnace through fixed conduits 21 operating in combination with a movable conduit 23 as described for the passage of the ore from hearth to hearth. In the construction illustrated the fixed conduits 21 through the hearth 11 are at the periphery thereof and, although two rabble arms are shown operating over the hearth 11 only the one which is vertically above the arm of the next hearth 12 is operative to feed ore into the conduits, the end rabbles of the other arm having been omitted to prevent ore being delivered at a time when the platform 22 is not sealing the other end of the conduit.

In applying the invention to a rectangular furnace the draught through the furnace passes from hearth to hearth through the usual corner flues, but when the invention is applied to a cylindrical furnace it is necessary to provide special flues for the ascending gases separate from the ore passages from hearth to hearth in order that dust shall be caused neither by the ascending gases meeting the falling ore nor by the gas flues being temporarily blocked and thereby choking the draught when a batch of ore falls from one hearth to another. For this purpose, in the case of a cylindrical furnace, the draught through the furnace passes from hearth to hearth through flues extending around the edge of the path of the rabble arm on each hearth as indicated in Figures 2 and 3. The flues are preferably made of metal and each comprises a central portion 25 which is built into the cylindrical wall 10 of the furnace. The flue 25 is formed with a lower enlargement 26 replacing part of the lower hearth 14 and providing an inlet below that hearth. The flue is also provided with an upper enlargement 27 replacing part of the upper hearth 13 and providing an outlet below that hearth, the draught through the flue from below the hearth 14 and above it being indicated by the arrows in Figure 3. The lower enlargement 26 does not extend above the rabbling level 19 of the hearth 14 nor does the upper enlargement 27 extend above the 100 105 110 115 120 125 130

rabbling level 19 of the hearth 13; the inner wall of the central portion 25 is preferably continuous with the inner surface of the furnace wall 10 so that the flue offers no obstruction to the passage of the rabble arm around the path of which it carries the furnace draught. The outlet of the flue from the enlargement 27 being above the level of ore on the hearth 14 there is no risk of the ore choking the flue.

10 The flues are preferably re-inforced by radial plates or partitions 28 to take the thrust of the arches of which they form a part.

15 The number and disposition of the flues 25, 26 and 27 may be varied but it is preferred to arrange those around the rabbling path of one hearth substantially diametrically opposite those around the rabbling path of the hearth above or below it. Thus the flues leading from below the hearth 14 to above it are shown in the left-hand side of Figure 2 whilst those leading from below to above the hearth 13 are shown at the right-hand side of Figure 2, those leading to the space below the hearth 14 from below the next lower hearth being also at the same side. In this manner the gases and draught through the furnace pass in a zig-zag fashion across successive hearths 20 and the flues are quite independent of the ore passages in size, number and disposition.

25 In some cases the flues, 25, 26, 27 may be replaced by other forms. For example, in a rectangular furnace any suitable construction of flue may be used disposed beyond the sphere of action of the rabble arms.

1. I claim:

30 1. In a mechanical ore roasting furnace comprising a series of superimposed hearths through which a rabble shaft extends with arms operating over the hearths, the combination with a fixed ore conduit opening through an upper hearth in the path of one end of the rabble arm operating thereon and depending to a point above the rabble arm on the hearth below, of a moving conduit 35 rotating with the shaft and disposed to register with the fixed conduit and thereby conduct ore to the rabbling level of the lower hearth, once in each revolution of the rabble shaft, substantially as specified.

35 2. In a mechanical ore roasting furnace comprising a series of superimposed hearths through which a rabble shaft extends with arms operating over the hearths, the combination with a fixed ore conduit opening through an upper hearth in the path of one end of the rabble arm operating thereon and depending to a point above the rabble arm on the hearth below, of a platform rotating with the shaft adapted to close the lower end of the fixed conduit, and a moving conduit 40 rotating with the shaft, opening in the platform at one end and adapted once in each revolution to register with the fixed conduit and

thereby conduct ore to an opening at its lower trailing edge at the rabbling level of the lower hearth, substantially as specified.

3. In a mechanical ore roasting furnace comprising a series of superimposed hearths through which a rabble shaft extends with arms operating over the hearths, the combination with a fixed ore conduit opening through an upper hearth in the path of one end of the rabble arm operating thereon and depending to a point above the rabble arm on the hearth below, of a concentric annulus rotating with the shaft and adapted to close the lower end of the fixed conduit, and a moving conduit extending from the annulus to the rabbling level of the lower hearth in rear of the arm operating thereon, substantially as specified.

4. In a mechanical ore roasting furnace comprising a series of superimposed hearths through which a rabble shaft extends with arms operating over the hearths, the combination with a fixed ore conduit opening through an upper hearth in the path of one end of the rabble arm operating thereon and depending to a point above the rabble arm on the hearth below, of a platform carried by the lower rabble arm extending in advance thereof to close the fixed conduit and a conduit moving with the lower rabble arm and opening at one end in the platform and at the other end in rear of the lower arm, substantially as specified.

5. In a cylindrical mechanical ore roasting furnace comprising a series of superimposed hearths through which a rabble shaft extends with arms operating over the hearths, the combination of conduits screening the passage of ore from hearth to hearth, and flues each comprising a central portion built in the furnace wall between two hearths with a lower enlargement replacing part of the lower hearth and providing its inlet and an upper enlargement replacing part of the upper hearth and providing its outlet, substantially as specified.

6. In a cylindrical mechanical ore roasting furnace comprising a series of superimposed hearths through which a rabble shaft extends with arms operating over the hearths, the combination of conduits screening the passage of ore from hearth to hearth, flues each comprising a central portion built in the furnace wall between two hearths with a lower enlargement replacing part of the lower hearth and providing its inlet and an upper enlargement replacing part of the upper hearth and providing its outlet, and plates extending radially of the cylindrical furnace for reinforcing said flues.

7. In a cylindrical mechanical ore roasting furnace comprising a series of superimposed hearths through which a rabble shaft extends with arms operating over the hearths, the combination of conduits screening the

passage of ore from hearth to hearth, flues each comprising a central portion built in the furnace wall between two hearths with a lower enlargement replacing part of the lower hearth and providing its inlet and an upper enlargement replacing part of the upper hearth and providing its outlet, the flue or flues around the rabbling path of one hearth being substantially diametrically opposite those around the rabbling path of the hearth above or below it.

In testimony whereof I hereunto affix my signature.

JOHN HARRIS.
